GEORGE O. PARKMAN, OF LINCOLNVILLE, AND JOHN M. TRUSSELL, OF BELFAST,
ASSIGNORS TO THEMSELVES AND AMBROSE STROUT, OF BELFAST, MAINE.

Letters Patent No. 90,383, dated May 25, 1869.

IMPROVEMENT IN FILTERS.

The Schedule referred to in these Letters Patent and making part of the same.

To all persons to whom these presents may come:

Be it known that we, GEORGE O. PARKMAN, of Lincolnville, and JOHN M. TRUSSELL, of Belfast, in the county of Waldo, and State of Maine, have invented a new and useful Filtering-Box or Apparatus; and we do hereby declare the same to be fully described in the following specification, and represented in the accompanying drawings, of which—

Figure 1 is a perspective elevation of it, and
Figure 2, a longitudinal section of it.

In such drawings—

A A' A" are a series of rectangular frames, made of wood or other proper material, and having a long slot made vertically through each bar of each frame.

Below or within these frames are two parallel bottom boards, B C, each of which is to be foraminous, or provided with numerous holes.

The frames are to be arranged, one directly over the other, and over the bottom boards, and with layers, *a a*, or masses of sponge, or other proper fibrous filtering equivalent, arranged between such frames, and also between the bottom boards.

Clamp-bolts *b b*, provided with screws, go up through the bottom boards and the slots of the frames, and receive nuts, *c c*, on their upper ends, such screws and

nuts serving to confine the boards and frames together, and to the layers of sponge or filtering-material; also to compress the latter to such extent as may be necessary, from time to time, in order to regulate its powers of filtration.

The slots of the bars of the frames, besides answering the purpose of receiving the bolts, aid greatly in holding the sponge in place.

To use the filtering-apparatus, water, or any liquid to be filtered, is to be suffered to run into it, from whence such liquid will flow out of the bottom, sides, and ends of the apparatus, or through the sponge and orifices thereof, and will be filtered or separated from any impurities or foreign matters capable of being removed by the process of filtration.

We claim the arrangement and combination of perforated bottom boards B C, the series of frames A A', A", the layers, *a*, of sponge, and the clamp-screws and nuts, the whole being substantially as and for the purpose hereinbefore specified.

GEORGE O. PARKMAN.
JOHN M. TRUSSELL.
